UNITED STATES PATENT OFFICE.

HENRY F. WELLMAN, OF ENGLEWOOD, ASSIGNOR TO THE SCHNEIDEWEND & LEE COMPANY, OF CHICAGO, ILLINOIS.

MACHINE FOR SHAVING PRINTERS' LEADS.

SPECIFICATION forming part of Letters Patent No. 348,804, dated September 7, 1886.

Application filed March 23, 1886. Serial No. 196,206. (No model.)

To all whom it may concern:

Be it known that I, HENRY F. WELLMAN, a citizen of the United States, residing in Englewood, county of Cook, and State of Illinois, have invented certain new and useful Improvements in Machines for Shaving Printers' Leads, Slugs, &c., of which the following is a specification.

This invention relates to improvements in machines for shaving printers' leads, slugs, &c., in which these articles in their cast and uneven condition are delivered to the knives for shaving through a suitable guide-recess, but is more particularly designed as an improvement on United States Letters Patent No. 314,384, granted W. F. Klose, March 24, 1885. As shown and described in this patent, there is a rigid connection between the blocks D and E, forming the top and bottom of the groove or recess through which the leads pass, thereby forming a rigid guideway for the said leads, of a fixed and unvarying depth, which construction practice has demonstrated is objectionable, for the reason that the said passage frequently becomes so obstructed as to render the stopping of the work necessary, in consequence of the jamming or wedging in the said groove of leads of too great a thickness to pass through the groove, and thereby necessitating the removal of the block E, in order to dislodge the obstruction. The removal of this block not only occasions a great loss of time and labor; but a still more serious objection arises, due to the fact that in removing this block the upper shaving-knife attached thereto is necessarily moved out of adjustment, and the readjustment of this knife requires the expenditure of no small amount of time and skill, and the most expert operator will lose several hours, and sometimes as much as a full day, in obtaining a perfect readjustment. Again, when a lead of a less thickness than the depth of a groove or recess is fed to the knives, the result is frequently such an uneven shaving of the lead, due to its wobbling and buckling while being forced along through said groove, as to render it practically useless, and necessitating its remelting and casting; hence it will be seen that all these evils are a necessary consequence of the rigid and therefore

objectionable construction of the guide groove or recess, as previously set forth.

The prime object of this invention is to have a yielding guideway for the leads, so constructed as to adapt itself to the varying thicknesses of leads, slugs, &c., while at all times forming a perfect guideway for the said leads, whereby the jamming and wedging of leads in said groove are obviated.

Another object is to provide a stationary support for the knives when set, disconnected from and independent of the yielding guideway, whereby the yielding block of said guideway may be removed without disturbing or in anywise interfering with the shaving-knives.

Further objects are to provide a yielding guideway for the leads, automatically and vertically adjustable, consisting of two blocks located one above the other, having a spring-cushion or yielding connection between them, and adapted to form suitable guides and supports for the lead-actuating mechanism of the machine, and to provide certain details of construction essential to the proper carrying out of my invention, and hereinafter fully described, and illustrated in the accompanying drawings, in which—

Figure 1 represents a side elevation of a lead-shaving machine with my invention applied thereto; Fig. 2, an enlarged detail side elevation of my yielding guideway; Fig. 3, an enlarged detail transverse vertical section on line $\alpha\alpha$, Fig. 1, and Fig. 4 an enlarged detail central vertical section through the guideway and knife-supporting block.

Similar letters of reference indicate the same parts in the several figures of the drawings.

The general construction and operation of the machine herein illustrated, with the exception of my improved guideway, are exactly similar in all respects to those shown and described in the aforesaid Letters Patent, and even the position and function of my guideway are the same; hence I do not deem any description of this prior construction necessary, except so far as any of the parts thereof may relate to or combine with my invention, of which the following is a detail description.

Referring by letter to the accompanying drawings, A indicates an oblong block or cast-

ing of suitable dimensions to correspond with and be attached to the bed B of the machine, to which it is rigidly secured. This block is slotted, as shown at *a*, to form a 5 guideway for a reciprocating slide-block, C, provided with a tongue, *b*, forming its guide, and fitting into a suitable recess formed in the bottom of the slot, as clearly illustrated in Fig. 3; but the preferred construction of 10 this block is that shown in Fig. 2, in which the part A' thereof is separated from the upper part, A², on the line *d d*, in order that the working-faces of the slot *a* may be planed 15 separately, to insure the true and accurate working of the reciprocating slide-block C. At the rear end of the said block A, and mounted thereon, is a head-block, D, carrying the side and upper shaving-knives, E and F, of the same or similar construction to that 20 previously shown, or any other that would perform the required work, and in the block A, opposing and working in conjunction with the upper cutter, is located the lower cutter, G, preferably exactly similar in construction 25 and operation to the said upper cutter. This head-block is made vertically adjustable, for the purpose of varying the thickness of the shaved or completed leads, by means of the slot *e* in a depending arm, *f*, of said head-block, 30 through which works a suitable set-screw, *g*, engaging the block A; and it is obvious that any adjustment of the head-block, carrying with it the cutter, will necessarily increase or diminish the distance between the cutting- 35 edges of the knives and the depth of the groove through which the completed leads are delivered; and I may here add that this adjustment is more especially designed for use in the latter connection, for the shaving-knives, it will be 40 remembered, have an adjustment entirely independent of either the head-block or the block A. Mounted on the said block A, forward of the head-block and totally disconnected therefrom, is another oblong block, H, 45 extending from its point of conjunction with the head-block to the forward end of the said block A, to which it is adjustably connected at this point by means of a set-screw, *h*, working through a vertically-elongated slot, *i*, in 50 an arm, *j*, depending from and cast with, or otherwise rigidly secured to, the forward end of the block H. Such a connection as just described, while it permits a vertical adjustment of the said block H, at the same time effect- 55 ually prevents any lateral movement thereof or the accidental unseating of said block, and acts as a valuable auxiliary in relieving from strain the other connections between these two blocks, the construction and opera- 60 tion of which are now to be described.

The upper face of the block H, at the points *k k*, Figs. 2 and 3, has vertical circular recesses bored therein, of a depth extending nearly through the block, and of a diameter to receive 65 and permit the vertical movement of set-screws *l* and spiral springs *m*, which latter are coiled about the shank of the screw, and have a bear-

ing or seat on the under side of the head thereof. The shanks of the screws pass freely through openings in the bottom thereof, and engage suitable screw-threaded sockets, *n*, provided in the upper surface of the block A, as clearly illustrated in Fig. 3, from which construction it will be seen that the spiral springs *m* are confined between the bottom of the recesses *k* and the heads of the screws *l*; and in consequence thereof the tension of said springs will be exerted downwardly to depress the block H toward the block A. 70 75

As before described, the blocks A and H 80 form the top and bottom of the groove *o*, through which the leads pass, and are both slotted vertically a distance sufficient to permit the reciprocations of the grip-carriage for gripping and pushing forward the leads to the 85 knives, consisting of the sliding blocks C and I, through which slots project and work the gripper-jaws *p p*; but as the construction and operation of these jaws, and, in fact, of the entire gripper-carriage, are identical with those 90 shown and described in said United States Letters Patent No. 314,384, to Klose; it is not necessary to describe these parts herein.

In practice the leads or slugs to be shaved are molded in strips about eighteen inches in 95 length, and of a thickness corresponding to the leads, slugs, or other printers' furniture for which they are intended to be used. About fifty of these leads are placed on a suitable automatic feed-table, (shown in Fig. 1 as attached to the forward end of the machine,) which leads are previously measured in bulk to find the thickness of the entire number combined, in order to determine the amount of shaving necessary on each individual strip, so 100 that the combined thickness of the strip when shaved will equal the thickness of a corresponding number of leads or slugs when ready for use. To produce the desired result it is obvious that great skill and accuracy are 105 necessarily employed in setting the knives at the desired point, for only the thinnest of shavings need be removed from each of the strips to aggregate the required thickness, and it frequently involves the outlay of hours 110 115 of time to obtain the necessary accuracy; hence it is all important that when once the knives are set nothing should occur which would necessitate the removal and consequently the readjustment of these knives; but 120 in the previous construction in which a rigid guideway for the leads is employed, such accidents are of frequent occurrence.

Owing to the necessarily varied thicknesses 125 of the leads when cast, and the fixed guideway through which they pass, frequent choking or stoppage of this guideway occurs as a result of the forcing therein of leads of a thickness too great to pass freely through the guideway, which of course necessitates the removal of the block forming the upper part of the guideway, in order to gain access to and remove the obstruction from the said guideway; and as in this prior construction the up- 130

per knife or cutter is secured to this removable block the knives are necessarily removed, therewith. As a consequence of such removal the knives must be readjusted thereafter in all cases, thus necessitating a great loss of valuable time and skill.

In addition to the foregoing objections there is another equally important—and that is, in cases where the leads to be shaved are of enough less thickness than the depth of the guideway to run too freely therethrough, in consequence of which these leads will be fed to the knives with an unsteady movement, productive of buckling of the leads and a consequent unevenness thereof when shaved, thereby rendering them unfit for use.

By the employment of my invention all these objections are overcome, for my yielding guideway will readily adapt itself to any unevenness, irregularity, or difference of thickness in different parts of the same lead strip, or of any number of different strips, the yielding connection between the two parts forming the guideway being held normally at the minimum thickness, but readily and easily adapted to expand from and return to that position when so actuated, and it will be observed that the tension or power of the spring forming a part of this yielding connection may be increased or decreased at will by manipulating the screw between the head of which and the bottom of the socket the said spring is confined; but even should the guideway become so obstructed as to necessitate the removal of the top block thereof, by reason of its being entirely disconnected from the head-block carrying the upper cutter, the said block may be readily removed without in anywise disturbing the adjustment of the cutter or knife.

I do not limit myself to the exact form or construction of the yielding connection herein shown and described, for various forms of mechanical devices may be employed and effect the same result, and would, therefore, be no departure from the spirit of my invention,

which consists, broadly, of a yielding guideway for the leads; and whether this yielding occurs in either the upper or lower parts of the guideway or between portions of either part thereof is not material.

50

Having described my invention, what I claim, and desire to secure by Letters Patent, is—

1. In a machine for shaving printers' leads, a yielding guideway for said lead between the feed and the shaving-knives thereof, substantially as described.

55

2. In a machine for shaving printers' leads, the upper and lower blocks and a recess or guideway between and formed by said blocks, in combination with a yielding connection between said blocks, substantially as described.

60

3. In a machine for shaving printers' leads, the upper and lower blocks, A and H, having a guideway therebetween formed by their juxtaposition, in combination with a screw working freely through said upper block, the shank thereof engaging the lower block, and an elastic cushion between said screw and the upper block, substantially as described.

65

4. In a machine for shaving printers' leads, the lower block carrying the under cutter or knife and the head-block mounted thereon, carrying the upper knife or cutter, in combination with the upper block mounted on said lower block forward of and disconnected from the said head-block, substantially as described.

70

5. In a machine for shaving printers' leads, the lower block carrying the under cutter or knife and the head-block mounted thereon, carrying the upper knife or cutter, in combination with the upper block mounted on said lower block forward of and disconnected from the said head-block, and a yielding connection between said upper and lower block, substantially as described.
